UNITED STATES PATENT OFFICE.

JAMES JULIUS STIFFEY, OF CONEMAUGH, PENNSYLVANIA.

PORTIÈRE, SHADE, AND CURTAIN HOLDER.

1,266,079.

Specification of Letters Patent.

Patented May 14, 1918.

Application filed May 7, 1917. Serial No. 166,970.

To all whom it may concern:

Be it known that I, JAMES JULIUS STIFFEY, a citizen of the United States, residing at Conemaugh, in the county of Cambria and State of Pennsylvania, have invented a new and useful Portière, Shade, and Curtain Holder, of which the following is a specification.

This invention has reference to holders for shades and curtains, and its object is to provide a device which may be applied to a window casing without the necessity of screws or nails to firmly hold it in place, the device having means which may be elongated within the casing to effect a cramping therein, and the cramping means is also employed for the purpose of holding brackets to the window casing, which brackets are designed to support a curtain pole, and, moreover, are provided with shade holding devices adjustable to accommodate shade rollers of different lengths, while the cramping device is susceptible of use by itself for installation in door openings to support portières, the cramping device being of peculiar construction for adjustment as to length and at the same time not only clamp the brackets against the wood work of the door or window frame, but engaging the wood work so as to prevent turning of the cramping device, or slipping thereof.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:

Figure 1 is an elevation of a small portion of the upper part of a window frame with the invention applied.

Fig. 2 is a longitudinal diametric section of the cramping or clamping member with some parts shown in elevation.

Fig. 3 is an elevation showing the application of the clamping or cramping member as a portière pole.

Figs. 4 and 5 are perspective views of the combined brackets and curtain holders to be

associated with the extension pole forming the cramping device.

Referring to the drawings there is shown an extension pole 1 composed of two tubular members 2, 3, respectively, the member 3 being of smaller diameter than the member 2 and telescoping therein, and also constituting the longer one of the two members in the particular showing of the drawings. While for short lengths the pole 1 may have its members 2 and 3 of about equal length, the purpose of the pole may be accomplished by having the member 3 longer than the member 2. The member 3 is provided at the end entering the member 2 with a plug 4, threaded to receive a threaded stem 5 extending longitudinally of the member 2 in the longitudinal axis thereof and supported at one end by a head or plug 6 in that end of the member 2 remote from that entered by the member 3. In the particular showing of Fig. 2 the plug 6 is indicated as made fast to the member 2 by a rivet 7, but it will be understood that any other means for the purpose may be employed, such as crimping, screw-threading, brazing, soldering or otherwise. The plug 6 is provided on the end remote from the stem 5 with an axially extended stud 8 forming a pivot or pintle for a block 9 to turn on, the stud 8 being conveniently headed, as indicated at 10, to retain the block 9 thereon. On opposite sides of the stud 8 the block 9 is provided with projecting pins 11.

That end of the pole section 3 remote from the block or nut 4 is closed by a plug 12 brazed or otherwise secured to the member 3 and also having projecting pins or studs 13 on opposite sides of its longitudinal axis and corresponding to the pins or studs 11. The pins or studs 11 and 13 have their free ends more or less pointed so they may be readily forced into the wood work of a window frame 14, as in Fig. 1, or a door frame 15, as in Fig. 3. With such an arrangement the pole 1 may be located in the frame 14 or 15, as the case may be, and when the pins or studs 11 and 13 have been suitably positioned the member 2 of the pole may be turned about its longitudinal axis in a direction to extend the pole by the unscrewing of the stem 5 from the nut 4. The turning of the member 2 is permitted because of its fit upon the member 3, and the swivel connection between the 108 110

blocks 6 and 9 due to the stud 8. As the stem 5 unscrews from the nut 4 the pins or studs 11 and 13 are forced into the wood until they can enter it no farther, and as soon as they begin to enter the wood the turning of the pole member 3 and the block 9 ceases. Ultimately the pressure is sufficient to prevent further rotation of the pole member 2 and the parts become firmly lodged in the frame. In the showing of Fig. 3 the pole 1 is utilizable by itself as a portière pole and needs no further description in this respect. The pole may be taken down at any time without the use of any kind of tools and without noticeable marring of the door frame in which it is lodged, since the studs 11 and 13 in actual practice need not exceed about one-sixteenth of an inch in length where entering the wood and about the same diameter.

In the case of a window such as shown in Fig. 1, where the frame 14 is indicated, there are provided two brackets 16 and 17, which may be exactly alike, except that they are made in rights and lefts, since they are designed to be located on opposite sides of the window frame 14. Each bracket has a flat basic portion 18 with perforations 19 therethrough spaced apart and of appropriate size to receive the studs 11 or 13, which, when the pole 1 is to be used in connection with the brackets 16 and 17, are long enough to not only pass through the basic members 18, but to enter for a short distance, say, one-sixteenth of an inch, more or less, into the wood of the frame against which the plates 18 are forced by the elongation of the pole 1.

In this manner the plates 18 become pressure or friction plates for the wood work, as well as forming the base portions of the brackets 16 and 17, and being of greater area than the block 9 and plug 12, protect the wood work from harm. Each bracket 16 and 17 has an extended arm 20 terminating at the end remote from the base 18 in a hook 21 suitably shaped and located to receive a curtain pole of customary kind. At a portion of the basic member 18 of each bracket there is formed an incompletely closed tubular guide 22, although, of course, the tube may be a complete tube. In the particular showing of the drawings the tube is of rectangular cross-section with two of its sides longer than the other two sides, and is arranged at a slight angle to the plane of the plate like base 18. Fitted to slide in each tube 22 is a flat bar 23 terminating at one end in an angle extension 24 with an angle extension of one bar provided with an elongated socket 25 and a similarly elongated passage 26 to receive the winding ends of spring shade rollers, while the extension 24 of the other bar 23 has 65 round passages 27 for the pintle ends of

spring shade rollers remote from the winding ends. By arranging the tubular guides 22 so as to be at a slight angle to the horizontal in the installed device, the bars 23 have always a tendency when mounted 70 on a window frame to move toward the middle of the window, thus bringing the extensions 24 toward each other. Now, when a curtain roller is mounted in the extensions 24 of the shade carrying bars 23, with the shade roller spaced away from the guide tubes 22, the tendency of the bars 23 is to approach each other, bringing the angular extensions 24 toward each other, and at the same time there is a tendency to cramp the 80 bars 23 in the guides 22, for any tendency to spread the shade holding bars 23 away from each other results in a cramping of these bars in the guides 22 because of the angular relation of the extensions 24 to the 85 direction of travel of the bars 22 in the guides.

When the device is installed in a window frame, as in Fig. 1, the studs 11 and 13 are caused to pass through the perforations 90 19 and by extending the bar 1 the plate-like bases of the brackets 16 are forced into intimate contact with the wood work of the window frame 14 and not only cramp the basic plates 18 tightly against the wood 95 work, but the studs 11 and 13 are forced slightly into the wood work, but sufficiently to hold all the parts against any possibility of displacement. Actual tests have shown that the device is capable of resisting displacement forces far greater than those to which it is ever liable to be subjected.

The shade roller brackets are readily adjustable at will to accommodate shade rollers of different lengths and automatically 105 hold the positions to which they are placed against all ordinary conditions of use. Still, whenever it is desirable, the shade roller may be removed and replaced without the necessity of the use of any tools 110 whatever, or the manipulation of any locking means. The whole device may be readily applied, or as readily dismantled by the simple expedient of turning the pole member 2 about the longitudinal axis of 115 the pole in a direction to screw the stem 5 into the pole member 3, thus shortening the effective length of the pole until the studs 11 and 13 are withdrawn from engaging relation to the wood work of the frame, 120 whereupon the whole structure may be removed from the window frame, the use of any tools whatever being entirely needless.

While the device of the invention may be made of any suitable material, the pole 1 125 may be readily constructed of tubular material of sufficient gage to be strong, yet light, and the brackets 16 and 17 may be readily stamped out of sheet metal, of which material the guides 22 may also be formed. The 130

shade roller supports 23 are readily formed out of flat bar metal, or any other suitable material, and the entire device is susceptible of manufacture in most part from structural materials obtainable upon the market, thus avoiding the necessity of devising and installing expensive machinery for the production of the device.

What is claimed is:—

- 10 1. A shade and curtain holder provided with an extension clamping pole comprising two telescoping members, and brackets with hook portions for receiving a curtain pole, each bracket terminating in a bearing plate, the extension pole having a plurality of projecting studs at each end and each bracket having passages for the studs, with the studs longer than the thickness of the plate ends of the brackets, whereby the shade and curtain holder is secured in a window frame solely by the projecting studs and because of the elongation of the clamping pole.
- 15 2. A device of the class described comprising plate-like members for engaging a window frame, each plate-like member hav-

ing a tubular guide at an angle to the plane of the plate-like member with each guide rising away from the other guide when in the installed position, means for securing 30 the plate-like members to a window frame, and shade-roller holding devices each comprising a bar carried by and freely movable lengthwise through a respective guide at an angle to the bar carried by the other guide 35 and each bar terminating at the end remote from the other bar in an angle extension having means for receiving a corresponding end of a shade roller, the angular relation of the bars to each other being such 40 that the shade roller holding devices cramp in the guides when subjected to forces tending to move the bars away one from the other in a straight line.

In testimony that I claim the foregoing 45 as my own, I have hereto affixed my signature in the presence of two witnesses.

JAMES JULIUS STIFFEY.
